UNITED STATES PATENT OFFICE.

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

MACHINE LUBRICATION.

Application filed March 8, 1926. Serial No. 93,157.

The present invention relates to improvements in machine lubrication, and has particular reference to an oil feed for the same.

The primary object of the invention is to provide means to properly and positively lubricate the working parts of machines, particularly the parts susceptible to wear by friction, and means whereby the lubricant may be brought to continued use.

10 Another object of the invention is to provide means whereby a supply of lubricant may be contained within the machine, together with means whereby this lubricant may be circulated to all parts of the machine 15 requiring lubrication.

Another object of the invention is to provide lubricating means which will operate substantially automatically, requiring little or no attention from the operator of the 20 machine.

A further object is to provide simple, inexpensive, strong and durable means efficiently adapted for the purposes specified.

Other objects and advantages, together 25 with the details of construction and method of operation of this invention, will become apparent during the course of the following description taken in connection with the accompanying drawings, the preferred form 30 only being shown by way of illustration. Many changes in the details and arrangement of parts may be made without departing from the spirit of the invention as set forth in the claims, and I therefore, do 35 not wish to be limited only to those shown and described.

Referring to the drawing in which like numerals designate like parts:

Figure 1 is a side elevation of a machine 40 embodying the invention;

Figure 2 is a longitudinal sectional view on line 2-2 of Figure 1;

Figure 3 is a transverse sectional view on line 4-4 of Figure 2.

45 Heretofore most machines have been dependent for lubrication on the thoughtfulness of the operator, who must lubricate his machine frequently by use of the old style oil can or upon an oil pump operated by 50 the machine and having a separate tube or pipe line leading therefrom to different parts of the machine that are to be lubricated. The latter is a very costly and unsatisfactory way of lubrication due to the failure

of the pump to operate properly by the 55 quick wearing of the parts within the pump, and the clogging of the same.

It, therefore, becomes a most important object of this invention to obviate these difficulties and to provide lubricating means 60 which shall be substantially automatic, and which shall properly and positively lubricate all the necessary points of contact, and which shall require little or no attention from the operator.

65 I have shown my invention applied to a so-called hand grinding lens machine having a grinding tool or lap 1 secured to the grinding shaft 2. The grinding shaft 2 is mounted in an upper bearing 3 and a lower bearing 4. The object of this invention is to lubricate the bearings 3 and 4 as well as other working parts to be described hereafter.

70 Surrounding the shaft 2 is an oil well or tank 5 in which a supply of lubricating oil 6 is maintained. The lower bearing 4 is lubricated by the oil 6 working down in the bearing through gravity, the top of the bearing being open to the oil tank well or tank 5.

75 The upper bearing 3 is lubricated by the oil 6 as follows: At the bottom of the tank 5 are passageways 7 leading down to a sub-oil well 8 at the bottom of the shaft 2. The shaft 2 is hollow, being, therefore, a 80 tube. In the bore of the shaft 2 is placed a tubular rod 9 having the bore 10 and a longitudinal slot or groove 11 throughout its length on the outside. There is a space 85 between the rod 9 and the inside of the hollow shaft 2. In this space and around the rod 9 is placed a spiral member 12 extending from the bottom of the shaft to the top of the rod 9 at the top of the upper bearing 3.

90 The spiral member 12 closely engages the sides of the bore of the shaft 2 and turns therewith. At the top of the upper bearing 3 is an oil chamber 13 communicating with the bore of the shaft 2 through an opening 14 in the shaft walls. Leading from the oil chamber 13 is a passage 15 communicating with the oil well or tank 5. Around the shaft 2 in the upper bearing 3 is a spiral 95 groove or oil channel 16. The oil 6 is carried from the oil chamber 8 up through the bore of the shaft 2 by the spiral member 12 as the shaft rotates. At the top of the bearing 3 the oil flows through the opening 100 105

14 into the chamber 13, thus flooding the top of the bearing. The oil is carried down through the bearing 3 by the spiral groove 16 as well as by gravity. Some of the over-
5 flow of the oil at the bearing 3 comes back into the oil chamber 8 through the bore 10 of the central rod 9, and some of it flows back into the tank 5 through the passage 15 from the chamber 13.

10 The rod 9 is held against rotation by the pin 17, on which the rod 9 is pivoted, as shown in Figure 2. The oil is driven up the slot 11 in the rod 9 by the advancing action of the rotating spiral member 12.

15 The shaft 2 is driven by the shaft 37 which is driven by the pulley 38 and belt 39. On the shaft 2 is a gear 40 driven by a gear 41 on the shaft 37. The bearings 42 and 43 for the shaft 37 are located in the tank 5 beneath the surface of the oil 6, which seeps into the bearing through the openings 44 and is carried along the bearings by the spiral grooves 45 on the shaft 37, the oil being driven along a channel 46 in the bearings back into the tank 5.

20 The lenses are held on the lap 1 by the pin 47 in the usual lever 48 pivoted at 49. The lap is surrounded by a protective pan 50. The driving shaft 2 is supported on a table 51.

25 While I have illustrated my invention as applied to a hand grinding lens machine it is apparent that the principles may be applied to other forms of bearing lubrication.

30 I have described the operations of my invention in describing the construction and parts of the machine, from which the construction and operation should be clear and from which it will be seen that I have provided simple, inexpensive and efficient means for carrying out the objects of the invention.

35 Having described my invention, I claim:

1. In a device of the character described, a hollow shaft, bearings for the shaft, a rod 45 within the hollow shaft having a longitudinal slot for the length of the rod on the outside thereof, a spiral member in the bore of the shaft and secured thereto, an oil well communicating with the spiral member, and 50 means for rotating the shaft whereby the spiral member will drive the oil from the

oil well along the longitudinal slot in the rod to the bearings.

2. In a device of the character described, a hollow shaft, bearings for the shaft, a rod 55 within the hollow shaft having a central bore and a longitudinal slot for the length of the rod on the outside thereof, a spiral member in the bore of the shaft and secured thereto, an oil well communicating with the spiral member, and means for rotating the shaft whereby the spiral member will drive the oil from the oil well along the longitudinal slot in the rod to the bearings.

3. In a device of the character described, a hollow shaft, bearings for the shaft, a rod 60 within the hollow shaft, a spiral member around the rod secured to the shaft, an oil well communicating with the spiral member, and means for rotating the shaft whereby 70 the spiral member will drive the oil from the oil well to the bearings.

4. In a device of the character described, a bearing, a tubular shaft in the bearing having an opening adjacent the bearing, means 75 to turn the shaft, an oil tank having an oil channel leading to one end of the shaft, an annular spiral oil carrier secured within the shaft to turn therewith, a rod in the spiral member having a longitudinal slot whereby 80 the oil is carried from the oil channel through the opening in the shaft to the bearing by the spiral member and the slot in the rod as the shaft is turned.

5. In a device of the character described, a bearing having an oil feed opening and an oil overflow opening therein, a tubular shaft in the bearing having an opening communicating with the bearing, means to turn the shaft, an oil tank communicating at one 90 point with the interior of the shaft and at another point with the oil overflow opening of the bearing, spiral means inside of the shaft adapted to carry the oil from the point of communication with the shaft to the bearing through the opening in the shaft and bearing and to the overflow opening in the bearing as the shaft is turned, and a rod within the spiral means having a longitudinal slot along which the oil may flow when 100 driven by the spiral means.

NELSON M. BAKER.
